No. 849,148.

PATENTED APR. 2, 1907.

F. W. LORD & F. W. ERICKSON.
PROTECTIVE DEVICE FOR ELECTRIC CIRCUITS.
APPLICATION FILED JAN. 28, 1907.

UNITED STATES PATENT OFFICE.

FREDERIC W. LORD AND FREDERIC WM. ERICKSON, OF NEW YORK, N. Y.

PROTECTIVE DEVICE FOR ELECTRIC CIRCUITS.

No. 849,148.

Specification of Letters Patent.

Patented April 2, 1907.

Application filed January 28, 1907. Serial No. 354,489.

To all whom it may concern:

Be it known that we, FREDERIC W. LORD and FREDERIC WM. ERICKSON, both residing at New York, in the county of New York and State of New York, have invented certain Improvements in Protective Devices for Electric Circuits, of which the following is a specification.

The invention about to be described relates to means for automatically grounding electric circuits when an abnormal current comes upon the line, such as lightning discharges and surges of potential, due to bad switching, open circuits, &c., which exceed the safety limit of the established circuit.

Many difficulties have arisen as to the proper safeguarding of the wires and appliances connected with transmission-lines since the installation of power plants employing a potential of considerable electromotive force. It is necessary to provide means for establishing an easy path for the abnormal currents to ground and separate therefrom the dynamic current and prevent it from following and continuing after the abnormal current has passed away; and the object of the present invention is to produce such means, which consists in providing a number of rapidly-moving air-gaps in the aggregate having sufficient resistance to safely prevent the normal current from discharging to ground and at the same time furnishing an opportunity for the abnormal discharges or surges to jump from one to the other of the various spark-gaps to the ground, all of which we will now proceed to describe in detail and point out in the appended claims.

Of the accompanying drawings, which illustrate the invention, Figure 1 is a side elevation, partly in section, of the invention. Fig. 2 is a portion of the device, partly in section, on line *x* *x* of Fig. 1. Figs. 3 and 4 are perspective views of details detached.

Referring to the drawings, a suitable base A supports the entire apparatus, preferably of some cast metal, and has attached thereto a lug for the ground-wire K, held in place by a set-screw *j*. Upon the base at each end are columns B B, supporting the oil-chambers C, between which is the rotating member D, immediately connected by shaft 10 with an electric motor M. The oil-chambers are constructed of porcelain or other insulating material, and their inner ends are circular in shape to conform to the peripheries of the rotating member D and are perfo-

rated by the orifices 2 2, through which the oil-wicks 3 project from the chambers to bear upon the rotating member. There are also indentations 4 in these surfaces externally across the same, which serve as air-spaces to allow the escape of gases and prevent disruptive action upon the rotating part D, which is adjusted close to the oil-chambers. The oil-chambers are made in square cross-section and are closed at their ends by a cap 5, which is held in place by a bolt 6 and a thumb-screw. The interior of each chamber is filled with cotton waste or wicking and is saturated by oil percolating from the reservoirs E. The reservoirs or oil-cups E may be of any of the commercial forms of oil-feeding devices ordinarily sold for lubricating machinery.

F F are insulating columns, of glass or porcelain, resting on and secured to the inner upper surfaces of the oil-chambers and are joined at their tops by the metal bar 7, which is held thereto by the bolts *b b*. Upon the top of the bar is a lug 8, into which, held by the set-screw 9, the branch wire J from the line-wire L W enters, and depending from the bar is the channel-piece 9, in which is secured the adjustable spark-gap electrode H, terminated in the curved serrated end *c*. The piece 9 has a slot *r*, through which the set-screw *p* passes into the piece 9, and by means of the screw *p* the electrode is adjusted to and from the rotating member D in the channel-piece.

A ground-wire electrode G is secured to the base A and terminates in a curved serrated end 11 under the rotating member D.

The rotating member D is supported upon the shaft 10 and is operated by the motor M and is a built-up wheel-shaped multiple electrode having the two outside metal disks *e e*, with hubs on their outer ends, interposed between which are the insulated disks *n* and *n*² and the spark-gap members *i*, alternating with each other. The latter members consist of a ring 12, from which extend two fingers 13 opposite each other, while each disk *n* is made with depressions 17 on one side like a mold adapted to receive and inclose the member *i*, with holes 15 for the bolts 16 and with a hole 14 for the shaft 10, while the disk *n*² is simply a flat one with holes for the shaft and bolts, and when in place the disks are shifted about so as to bring the fingers disposed evenly on the periphery of the wheel, and the parts are held in place and

together by the bolts 16. The diameter of the members *i* is a little less than that of the disks in order that arcs may not pass from the point of one to that of another. A plurality of fingers, poles, or arms 13 may extend from the ring.

In the working of the device a discharge from the line-wire to the branch *J* is carried from the electrode *H* over the gap *c* onto one of the movable members *i*, thence to the ground-wire electrode *G*.

It is evident that a static discharge can easily jump over the air-gaps as, above stated, after which the dynamic current will follow a similar path; but a continual disruption caused by the flow of dynamic current is interrupted by the rotating member *D*, owing to the travel of the electrodes or members *i* through a restricted arc and segment on the curved ends of the oil-chambers. To further carry out this idea, the wicks bear against the surfaces of said segments, supplying a thin film of oil at the same time, which has the effect of brushing out the disturbing arc which might have a tendency to carry across from the electrodes *H* to *I*.

It will be seen that the sections of the rotating member *D* passing the oil-chamber are constantly swept or brushed by the oil-wicks, and any tendency of an arc to be drawn out is prevented, and as the path for an arc is constantly being transferred from one electrode or member *i* to another the danger is eliminated. The tendency to perpetuate an arc is also diminished by the nearness of the oil-chambers to the rotating member *D*, the sides of which may be brought very close to each other, so that the intervening space is filled with an oil-film.

We prefer to make the oil-chambers wider than the rotating member *D*, so the sides of the latter will be enveloped by the former, as shown by heavy dotted line *X* on Fig. 1.

The insulating-disks *n* of the rotating disk are made quite thick and preferably of porcelain, which will not absorb heat readily and will part with the same very easily, all of which tends to keep the electrodes *i* (which are surrounded on all sides by the disks, except their ends) cool and favors the reduction of arcs.

We claim as our invention—

1. The combination in a protective device of an air-gap electrode connected to a line-wire, a second air-gap electrode connected to ground, and a rotatable member composed of a plurality of electrodes each adapted to form a bridge between the line-wire and ground-electrodes, with means for partly inclosing the rotating electrodes and providing a film of oil thereover.

2. The combination in a protective device of an air-gap electrode connected to a line-wire, a second air-gap electrode connected to ground, and a rotatable member composed of

a plurality of electrodes adapted to form a continuous series of bridges between the line-wire and ground-electrodes, with means for partly inclosing the rotating electrodes and providing a film of oil thereover.

3. The combination in a protective device of an air-gap electrode connected to a line-wire, a second air-gap electrode connected to ground, and a rotatable member composed of a plurality of electrodes adapted to form a continuous series of bridges between the line-wire and ground-electrodes insulated from each other, with insulating-surfaces partly inclosing the rotating electrodes through which oil is conveyed to form a film between said electrodes.

4. The combination in a protective device of an air-gap electrode connected to a line-wire, a second air-gap electrode connected to ground, and a rotatable member upon a shaft with a motor, composed of a plurality of electrodes separated by insulation, each electrode consisting of a ring from which extend two or more poles or arms to the periphery of the member, with curved insulating-surfaces partly inclosing the member through which oil is made to exude and form a film between the poles.

5. The combination in a protective device of an adjustable air-gap electrode connected to a line-wire, a second air-gap electrode connected to ground, and a rotatable member upon a shaft with a motor composed of a plurality of electrodes embedded in insulation each electrode consisting of a ring from which radiate two or more poles or arms to the periphery of the member, with curved insulating-walls partly inclosing the member and forming a side of a chamber from which oil is caused to exude by capillary attraction and form a film between the said poles.

6. The combination in a protective device of an adjustable air-gap electrode connected to a line-wire, a second air-gap electrode connected to ground, and a rotatable member upon a shaft with a motor composed of a plurality of electrodes each of which is adapted to form a bridge between the line and ground electrode serially, each electrode separated from the other by insulating-disks, all of which are held closely together by bolts, with curved insulating perforated walls partly inclosing the rotatable member and forming a side of a chamber from which oil is caused to flow by capillary attraction and form a film between the said poles.

7. The combination in a protective device of a ground-electrode, a rotatable electrode and a line-electrode arranged over each other upon a suitable support with an insulating-chamber on each side of the second electrode whose inner surfaces conform to the contour thereof and are perforated to permit wicks to be drawn therethrough, and an oil-reservoir communication with each chamber, the sec-

ond or rotatable electrode composed of a plurality of poles extending from central rings and embedded in insulating-disks, all secured by bolts and upon a shaft with a motor, as
5 set forth.

In testimony whereof we have signed our names to this specification, in the presence of

two subscribing witnesses, this 23d day of January, 1907.
